OF RICHMOND, VIRGINIA

BED WARDROBE

Application filed January 10, 1929. Serial No. 331,408.

In these days of small rooms, especially in apartment houses, it is a serious problem to find storage or holding room or space and the problem is especially acute as to articles such as parts of wearing apparel that require repeated temporary storage. The object of my invention is to meet this situation by utilizing space that otherwise is not utilized or is wasted. Beneath the ordinary bed, as is well known, is a large amount of space and in producing my invention, I make use of that space.

My invention consists in whatever is described by or is included within the terms or scope of the appended claim.

In the drawings:

Fig. 1 is a perspective view illustrating an embodiment of my invention, the holder or receptacle being shown in full lines partially withdrawn from under the bed to give access to its interior;

Fig. 2 is a vertical section showing the holder or receptacle in a closed position;

Fig. 3 is a detail view in section of a different embodiment of my invention.

Generally described, my invention comprehends the combination or association with a bed supported on legs so as to provide a space of substantial depth from the mattress or springs to the floor, of a movable box or container whose dimensions utilize to the best possible advantage the space beneath the bed, and having such form and appearance as to be harmonious with the bed structure and which is capable of movement between a position under the bed to one sufficiently from beneath the bed to give access to its interior for placing therein or removal therefrom of articles of clothing or wearing apparel, or any other objects requiring to be thus temporarily stored away. The size and proportions of the box or holder may be such as to permit its placing under the bed from the side thereof, and there may be one for each side of the bed or at the foot; or there could be boxes or receptacles at both sides and the foot of the bed.

In the drawings, I show a portion of an ordinary bed, 10, and a closed box holder comprising a body, 11, of bottom and four ver-

tical side walls, and a top or cover, 12, the interior of the body being divided by partitions into as many separate compartments as may be desired, and of different dimensions to readily hold various articles of apparel. The dimensions vertically and longitudinally are such as to be slightly less than the vertical and longitudinal dimensions of the space beneath the bed and the dimensions transversely are such that from front to back they will not be greater than will allow the complete placing of the box or holder within a vertical plane passing through the outer side of the side rail or the end rail of the bedstead, according to the position of the receptacle or holder with reference to the bed.

Wheels or casters or domes of silence are applied to the bottom of the body to enable the movement of the receptacle or holder under and from beneath the bed easily effected and without injury to floor or floor covering.

The cover, 12, may be hinged or pivoted, but is preferably horizontally slidable so that it will be unnecessary wholly to withdraw the holder or receptacle for beneath the bed to give access to its interior, which would be necessary if the cover is hinged. And of course, a hinged cover would require the provision of some means to hold it in an open position to prevent accidental falling thereof to a closed position.

Suitable handles are applied preferably to the front wall to facilitate drawing the receptacle or holder from beneath the bed.

It will be seen that in reality, my invention provides what may well be termed an "under-bed wardrobe."

The finish or appearance of this under-bed wardrobe may match or harmonize with that of the bed.

The sliding top or cover has at each end a downwardly extending flange, 13, that overlaps and lies against the upper edge of the box end both for the purpose of keeping the cover in position against endwise movement and to make a dust-tight joint and at the rear it has a similar flange, 14, for the two purposes of making a dust-tight joint and to constitute a stop to forward movement of the cover when it is drawn forward to its

closed position. On the underside of the cover is a downwardly extending lug or projection, 15, which, when the cover is moved backward strikes the back wall of the box and while allowing continued movement of the box. 5 In testimony whereof I hereunto affix my signature.

ANNIE LAURIE BROOKER. 70

thus prevents the cover being pushed wholly off the top of the box, and this stop, 15, may be so located as to leave a substantial portion of the cover at the front still lying over the top of the box and yet not interfere with 10 access to the interior of the box.

Automatic closing and unclosing the box by providing devices that cooperate with the bedstead may be and preferably is done. Thus, as shown in Figs. 1 and 2, I attach 15 to the cover at each end a finger, 16, adapted to project upward in position to bear against the inner side of the side rail of the bed, so that when the box is drawn outward from beneath the bed, it will slide outward leaving 20 the cover behind and said finger, 16, is pivoted so that it may be swung from a vertical position to a horizontal position where it affords no obstruction to the outward movement of the cover with the box should it not 25 be desired to have the automatic action in which case the cover is moved to open the box by hand. When the finger, 16, is in position to engage the side rail of the bedstead to hold the cover for moving outward with the box, 30 the automatic closing of the box is effected by a suitable connection with the bedstead which as shown in Figs. 1 and 2 is a strap or straps, 17, of leather or webbing having a rigid hook, 18, to catch over the edge of the 35 side rail of the bed, and the strap attached at its other end to the cover at or near the rear edge. When the stop finger, 16, is not used and the cover moves outward with the box when withdrawn from beneath the bed, 40 the flexible strap will permit that action and the strap, of course, will serve as a stop to prevent the box being moved too far under the bed.

As shown in Fig. 3 the cover may have 45 at its rear end sheet metal straps, 19, to catch over the side rail of the bed, and thereby the automatic opening and closing of the box be effected because the cover will be restrained from movement both when the box is drawn 50 outward from beneath the bed and when it is pushed inward. Said straps also prevent the box being moved too far beneath the bed.

What I claim is:—

In combination with a bed, a box or holder 55 normally under the bed and movable from beneath the bed having dimensions vertically and longitudinally that substantially utilize the space beneath the bed, a cover for the box that is movable bodily with the box, means 60 to connect cover and bed that limit movement of the box when box and cover are moved beneath the bed and coacting disconnected means on cover and bed that stop movement of the cover when cover and box 65 are drawn together from beneath the bed.
